UNITED STATES PATENT OFFICE.

WILLIAM HAGERTY, OF PHILADELPHIA, PENNSYLVANIA.

BAKE-PAN.

SPECIFICATION forming part of Letters Patent No. 366,478, dated July 12, 1887.

Application filed March 19, 1887. Serial No. 231,512. (No model.)

To all whom it may concern:

Be it known that I, WILLIAM HAGERTY, a citizen of the United States, residing in the city and county of Philadelphia, State of Pennsylvania, have invented a new and useful Improvement in Bake-Pans, which improvement is fully set forth in the following specification and accompanying drawings, in which—

Figure 1 represents a bottom plan view, partly sectional, of a baker's pan embodying my invention. Fig. 2 represents a section in line $x x$, Fig. 1, on an enlarged scale. Fig. 3 represents a section in line $y y$, Fig. 1, on an enlarged scale. Fig. 4 represents a section in line $z z$, Fig. 1, on an enlarged scale.

Similar letters of reference indicate corresponding parts in the several figures.

It is well known that owing to the severe usage to which bakers' pans are subjected they are liable to break at or about the joints of the wire or round iron at the rims or beads of the pan. In said cases said joints are soldered; but they form irregularities at contiguous parts of the pan and possess no strength, hence are objectionable, and do not render the required service.

My invention is designed to remedy the defect; and it consists in re-enforcing the joint, as will be hereinafter fully set forth.

Referring to the drawings, A represents a baker's pan, which, excepting the feature of my invention applied thereto, is of usual construction.

B represents the wire or round iron at the bead or rim of the pan, the ends of which meet at either of the sides, as in the drawings, or in some cases at either of the corners, the joint being shown at a , Fig. 4.

C represents a sleeve which is slipped over or encircles the ends of the wire B, thus covering the joint a and producing a continuity of the wire, thus re-enforcing the wire at and about said joint, whereby any strain on the pan at a place coincident with the joint a is borne by the sleeve, and breakage of the pan thereat under ordinary circumstances is prevented.

The metal of the pan is bent over the sleeve, partly or entirely concealing the same.

Having thus described my invention, what I claim as new, and desire to secure by Letters Patent, is—

1. A bake-pan having a beading-wire at its rim and provided with a re-enforce for said wire at its connecting ends, all substantially as described.

2. A bake-pan having a beading-wire at its rim and provided with a sleeve embracing the connecting ends or joints of said wire, all substantially as described.

WM. HAGERTY.
